Attorneys.

UNITED STATES PATENT OFFICE.

EDMUND F. HOSKIN, OF CHICAGO, ILLINOIS, ASSIGNOR TO WILLIAM A. SPINKS & CO., OF CHICAGO, ILLINOIS, A CORPORATION OF ILLINOIS.

BILLIARD TABLE.

Application filed September 8, 1924. Serial No. 736,596.

To all whom it may concern:

Be it known that I, EDMUND F. HOSKIN, a citizen of the United States, residing at Chicago, in the county of Cook and State 5 of Illinois, have invented a new and useful Improvement in Billiard Tables, of which the following is a specification.

This invention relates to improvements in billiard tables, and more especially to 10 a billiard table having a bed made of molded material instead of natural slate as is ordinarily used. Any kind of molded material which will provide a hard, smooth, solid bed resembling natural slate may be 15 used. I have found that Portland cement impregnated with sulphur under heat and in a partial vacuum will very closely resemble the natural slate. Such material may be cast or molded in any form desired 20 and will be found to be hard and will take a fine polish.

By the use of my invention, a billiard table may be made lighter and cheaper than with the use of natural slate and also 25 will be more serviceable. By the use of molded material for forming the bed of the billiard table, it is easier to get the adjoining portions of the bed in proper registry and make the same lie in a plane. It 30 is also easier, by the use of my invention, to set up the billiard table, level with same, fasten the cushion rails, and put on the cloth. Other features and advantages of 35 my invention will appear more fully as I proceed with my specification.

In that form of device embodying the features of my invention shown in the accompanying drawings, Fig. 1 is a top plan view of a billiard table showing a portion 40 of the cushion rails and the cloth removed at one of the corners, Fig. 2 is a view taken as indicated by the line 2-2, Fig. 1, Fig. 3 is a view taken as indicated by the line 3-3, Fig. 1, and Fig. 4 is a bottom view, 45 on a smaller scale, of one of the three sections of the bed.

As shown in the drawings, the bed of the table is preferably made in three similar rectangular sections indicated by A, B and 50 C. One of the sections is shown separately in Fig. 4. Since these three sections are similar in construction, I will describe in detail but one. For example, the section A comprises a rectangular sheet of molded

material provided with a thickened depending border or edge as indicated by 10. On the under side there are also provided longitudinal and cross ribs, 11 and 12 respectively, for the purpose of giving the necessary rigidity and strength to the bed. 55

The lower outer edge of the border 10, except where the sections of the bed are adjacent to each other, is rabbeted as indicated by 13. Within the rabbet thus formed is placed a wooden strip, 14, which is held in position by screws 15 having their threaded ends engaging with nuts 16 which are molded or cast in the material 60 when the sections of the bed are formed. The strip 14 is for the purpose of receiving 65 tacks 17 which hold the edge of the billiard cloth 18. This construction is a decided improvement over the method used for fastening the cloth when natural slate is employed. In such cases, it is necessary to put 70 under the slate what is called a slate frame in order to receive the tacks to hold the cloth in position. In my present device, this slate frame may be entirely dispensed with. 75

Each of the three sections has imbedded in the thickened portion 10 at each end two nuts, 19. Above and below each of the nuts 19 is a hole 20 extending vertically through the border. Each of the nuts 19 80 is adapted to receive the leveling screw 21 having its lower end slightly rounded as indicated by 21^a and resting in a metallic cup 22 mounted on the upper surface of the table frame 23. The meeting edges of the 85 three sections of the bed are provided with dowel pins 24 to assist in holding the sections in proper registry. By means of the leveling screws 21, the various sections of the bed can be adjusted so that they will 90 all lie at their proper level. The method of doing this is obvious. The screws 21 are screwed downwardly or upwardly until the various sections lie in the proper plane. This method of leveling the bed of the table 95 is a great improvement over the means heretofore commonly used when natural slate is employed. When natural slate is used, the slabs forming the section of the bed ordinarily are somewhat rough on the bottom so that it is necessary to employ in 100 connection with each slab, a slate frame which is properly hewn and fastened to the

lower surface of the slab so as to give the proper thickness throughout. When these slabs with the slate frames thus attached are laid on the table frame, they must be 5 shimmed, or wedged upwardly or downwardly until the correct level is obtained. This is a rather difficult and uncertain process. Also, after once being adjusted, it is very difficult to make readjustments 10 which are frequently required later. By the use of my invention, the level of the bed, or of any of its sections, may be changed, as desired, at any time, very easily, by merely adjusting the leveling screws 21.

15 The following means are provided for holding the cushion rails 25 in position. Molded or cast in the thickened border portion of each of the bed sections at each end thereof are two nuts, 26. The end sections 20 A and C also have two nuts like this in the thickened portions of their sides which form the ends of the complete table. The nuts 26 are adapted to receive screws 27 which extend through the cushion rails 25 25 as shown. This construction is also a great improvement over the construction used when natural slate is employed. In such cases, it has always been quite difficult to fasten the cushion rail in place to the slate.

30 A nut adapted to engage a screw had to be fastened in the natural slate. This was usually done by cutting a large hole in the slate, dropping a nut in place and cementing it there. Frequently the nuts became 35 loose or dislodged. By using cast or molded material, it is possible to cast the nuts 26 firmly in place where they remain permanently. The same is true in fastening the nuts 19 and 16 in place. All these nuts are 40 firmly held in position because they are cast or molded in place as the sections of the slate bed are formed.

While I have shown and described certain embodiments of my invention, it is to be 45 understood that it is capable of many modifications. Changes, therefore, in the construction and arrangement may be made without departing from the spirit and scope 50 of the invention as disclosed in the appended claims, in which it is my intention to claim all novelty inherent in my invention as broadly as possible in view of the prior art.

What I claim as new and desire to secure 55 by Letters Patent, is:

- 55 1. A billiard table bed made of molded material having a thickened border portion.
2. A billiard table bed made of molded material having a thickened border portion and provided with a stiffening rib.
- 60 3. A billiard table bed made of molded material having a thickened border portion

and provided with transverse and longitudinal stiffening ribs.

4. A billiard table bed made of molded material having a thickened border portion, 65 and a plurality of nuts imbedded in said thickened border portion, each of said nuts having a leveling screw extending therethrough with its lower end adapted to engage the upper surface of a table frame. 70

5. A billiard table bed formed of molded material having a thickened border portion, the lower outer edge of said border portion being rabbeted, and a cloth-holding strip held in said rabbet by screws having their 75 inner ends engaging with nuts imbedded in the thickened border portion.

6. A billiard table bed formed of molded material having a thickened border portion, and a plurality of nuts imbedded in said border portion, each of said nuts adapted to receive the threaded end of a cushion retaining screw. 80

7. A billiard table bed formed of molded material having a thickened border portion, 85 a plurality of nuts imbedded in said border portion during the casting or molding thereof, and a plurality of leveling screws adapted to engage said nuts.

8. A billiard table bed formed of molded material having a thickened border portion, 90 a plurality of nuts imbedded in said border portion during the casting or molding thereof, and a plurality of cushion rail retaining screws adapted to engage said nuts. 95

9. A billiard table bed formed of molded material having a thickened border portion, a rabbet in the lower outer edge of said thickened border portion, a plurality of nuts imbedded in said thickened border portion adjacent said rabbet during the casting or 100 molding of the bed, a cloth retaining strip lying in said rabbet, and a plurality of screws extending through said cloth retaining strip and entering said nuts above mentioned. 105

10. A billiard table bed formed of molded material having a thickened border portion, a recess in the outer side face of said thickened border portion, a plurality of nuts embedded in said thickened border portion adjacent said recess during the casting or 110 molding of the bed, a cloth retaining strip lying in said recess, and a plurality of screws extending through said cloth retaining strip and entering said nuts above mentioned. 115

In witness whereof I have hereunto set my hand and seal this 5th day of September, 1924.

EDMUND F. HOSKIN. [L. S.]
